METHOD AND APPARATUS FOR HEATING FLUIDS

Joseph G. Alther, Chicago, Ill., assignor to Universal Oil Products Company, Chicago, Ill., a corporation of South Dakota

Application June 4, 1932, Serial No. 615,358

12 Claims. (Cl. 122—356)

This invention particularly relates to an improved method and means of heating fluids substantially by convection or fluid heat during their passage in a continuous stream through a conduit which comprise subjecting the maximum surface of the fluid conduit to high rates of heating in order to obtain a high average rate of heat input over the entire surface of the conduit.

While the invention may be applied to the heating of fluids generally, its preferred use is in the heating of hydrocarbon oils and it is especially useful in the cracking of hydrocarbon oils.

More particularly the invention refers to an improved method and means for heating fluids wherein a heat carrying medium, e. g. hot combustion gases, are directed by positive means to opposite sides of the conduit through which the fluid is passing, whereby they are uniformly distributed over the surface of the fluid conduit in such a manner as to effect an average rate of heating around the entire periphery of the conduit approaching the maximum rate of heating and whereby direct control for any desired rate of heat input is obtained. Among other advantages of the present invention may be mentioned (a) the control of velocity, pressure drop and turbulence in the fluid conduit irrespective of the total quantity of oil undergoing treatment at one time (b) high average heat input over the entire surface of the fluid conduit and uniform application of heat to opposite sides of the conduit (c) flexibility of control of heat application to obtain any desired rate of heat input by direct control of the firing conditions and direct control of heat distribution to obtain any desired heating curve for the material undergoing treatment (d) high tube efficiency as compared with convection heating methods of conventional character. Maximum capacity for a fluid conduit of given size or, vice versa, minimum tube surface for a given capacity, (e) quick heating of the fluid to a high temperature in a minimum of time. As applied to the conversion of hydrocarbon oils, this feature reduces excessive cracking and gas formation as well as the formation and deposition of coke in the heating zone or fluid conduit, thereby increasing the yield and antiknock rating of the motor fuel product as compared with the same cracking process employing heating methods which necessitate lower rates of heating and longer time in the heating zone. The use of the invention may also reduce installation, operating and maintenance costs and increases the safety factor. By the application of the invention, a large quantity of oil may

receive the same heat treatment as a small quantity of oil with all of the resulting advantages.

In the heating of fluids substantially by convection, it is common practice to pass hot combustion gases over the fluid conduit, comprising 5 a plurality of tubes through which the fluid flows in a continuous stream. When the tubes are arranged in rows parallel to the flow of combustion gases there is a tendency for the gases to channel through the space between the rows of 10 tubes, permitting a large volume of hot gases to pass through the tube bank without coming into intimate contact with the tubes and transmitting heat to the fluid. To overcome this channeling of the hot combustion products it has become 15 common practice to place the tubes of the fluid conduit in staggered formation so that the path of flow of the hot gases is continually changed in an attempt to distribute them more uniformly around the tubes and obtain more intimate and 20 uniform contact between the combustion gases and the tube surfaces. However, such methods do not secure positive uniform distribution of the gases about the tubes, different tubes in the same row perpendicular to the general direction 25 of flow of the combustion gases often being heated at different rates and the uniform distribution of hot gases around the circumference of each tube being the exception rather than the rule. The staggered arrangement of tubes 30 which breaks up the stream of gases, changing their uni-directional flow, offers increased resistance to the flow of gases which, with a given draft condition, decreases the volume of gases which may pass through the tube bank in a 35 given time, thereby decreasing the velocity and heating efficiency of the gases which come into actual contact with the tube surfaces.

In the operation of the process of the present invention, the hot combustion gases, which furnish heat substantially by convection to fluid passing in a continuous stream through the tubes of a fluid conduit, are directed against opposite sides of the tubes in such a manner that a substantially uniform distribution of gases and substantially uniform heating is obtained on opposite sides of each individual tube in the fluid conduit. This insures a high average heat input per unit area of tube surface for any given maximum rate of heating, which means high tube efficiency 40 and maximum capacity for a fluid conduit of given size or, vice versa, a minimum of heating surface for a given capacity. Also, by employing the features of the present invention, wide differences in heat intensity at different points 45 50 55

around the circumference of the same tube are avoided, thereby eliminating stresses, due to unequal expansion, and increasing the safety of a tube of given diameter and wall thickness or 5 permitting the use of a thinner wall in tubes of the same diameter. This reduces the cost of installation. Also, as a result of increasing the average rate of heat input, the time of treatment 10 may be reduced and overcracking minimized, which results in smaller gas production per barrel of oil being treated, greater gasoline yield and higher octane number, as stated previously.

As a further feature of the invention, the fluid conduit may be divided into a plurality of tube 15 banks each of which is independently heated from opposite sides. The various tube banks may be connected either in series or in parallel. When connected in series, this arrangement provides a method and means of obtaining a close 20 control over the intensity of heating in each section of the entire fluid conduit, independent of that in any other section so that the rate of heat input may be varied in different sections of the fluid conduit to suit requirements or may be 25 maintained substantially uniform in any or all of the various sections of the heating coil or fluid conduit. This makes it possible to employ any desired type of heating curve (i. e. any desired rate of temperature rise in various sections of the 30 furnace) and permits changing the heating curve at will by simply changing the firing conditions without any change in the furnace structure or in the flow through the heating coil.

With parallel flow through the various sections 35 of the heating coil, the features of the present invention permit increasing the capacity of the furnace by the simple addition of unit sections comprising additional tube banks without changing any of the heating characteristics. For example, given a furnace with a fluid conduit comprising two banks of heating tubes, the tubes of each bank being connected in series and the two banks being connected in parallel, the capacity of the furnace may be doubled by the addition of 40 two similar unit sections having two similar banks of tubes, without increasing the pressure drop through the total fluid conduit, which now comprises the four tube banks connected in parallel, without changing the velocity of the fluid flowing 45 through the heating coil and without otherwise changing the heating conditions such as the intensity of heating in each unit section and each portion of the various unit sections of the furnace and without changing the type of heating 50 curve.

A multiple-unit furnace of the type provided by the features of the present invention may also be utilized to special advantage, as applied to the conversion of hydrocarbon oils, when it is desirable to subject two or more different types of oil to independently controlled heating conditions in the same cracking system. In this connection, any number of unit sections of the same furnace may be employed for any number of 60 different oils, one or more sections being utilized for each type of oil with independently controlled heating conditions in each unit section.

In the accompanying drawings,

Figure 1 is a sectional end elevation of the furnace and Figure 2 is a sectional side elevation. Figures 3 and 4 of the drawings illustrate a somewhat different form of furnace structure also embodying the features of the present invention. Figure 3 is a sectional end elevation and Figure 75 4 is a sectional side view. Figures 5, 6 and 7 in-

dicate three different methods of connecting the various tube banks of the fluid conduit in either of the different specific forms of furnace structure illustrated in Figures 1, 2, 3 and 4. Figure 5 shows the tube banks connected in parallel while Figures 6 and 7 indicate two different methods of connecting the several tube banks for series flow of fluid therethrough. Figure 8 of the drawings illustrates several types of heating curves which may be obtained in accordance with the provisions of the present invention in either of the specific types of furnace illustrated.

Referring to Figures 1 and 2 of the drawings, the main furnace structure comprises side walls 1 and 1', end walls 2 and 2', a roof 3 and a floor 4. The fluid conduit comprises a multiplicity of vertical tube banks 5, 6 and 7, each consisting of a number of horizontally disposed tubes 8, extending between end walls 2 and 2' of the furnace. The tubes of each of the vertical rows or banks 20 are connected in series by means of suitable headers or return bends 9. Inlet and outlet ports 10 are provided at opposite ends of each bank of tubes each of which may be utilized as either the inlet or the outlet port so that the flow of oil 25 or other fluid to be heated may be either upward or downward through any individual bank of tubes, as desired.

In the particular form of furnace here illustrated, firing and combustion tunnels 11, 12, 13, 14, 15 and 16 are provided above the main furnace structure, one tunnel being provided on each side of each vertical bank or row of tubes. The tunnels may be supplied with any desired form of fuel such as oil gas, or pulverized solid fuel by 35 means of suitable burners, not shown in the drawings, through firing ports located in the top. Hot combustion gases pass from the firing tunnels 11, 12, 13, 14, 15 and 16 through openings 17 in the roof of the furnace into the respective 40 distributing zones 18, 19, 20, 21, 22 and 23, located on opposite sides of the respective tube banks 5, 6 and 7.

The tube banks 5, 6 and 7, respectively, are located in heating zones 25, 26 and 27. Heating 45 zone 25 is separated from distributing zones 18 and 19 by perforated walls 28 and 29, respectively. Heating zone 26 is separated from distributing zones 20 and 21 by perforated walls 30 and 31, respectively. Heating zone 27 is separated from distributing zones 22 and 23 by perforated walls 32 and 33, respectively. In this manner the entire furnace structure is divided into three unit sections, each of which comprises a bank of tubes within a heating zone 55 with a firing tunnel and distributing zone on each side of the vertical center line through the tube bank, as viewed from the end of the furnace, as in Figure 1.

Equal quantities of hot combustion gases are 60 directed to the opposite sides of the tubes of each bank through perforations or openings 34 in walls 28, 29, 30, 31, 32 and 33, passing downward over the tube surfaces in such a manner as to heat the opposite sides of each individual tube 65 equally.

Firing conditions may be so controlled that combustion is substantially completed in the firing tunnels 11, 12, 13, 14, 15 and 16 or some combustion may be allowed in the distributing 70 compartments 18, 19, 20, 21, 22 and 23. Particularly in the latter case, however, the walls 28, 29, 30, 31, 32 and 33 are constructed of suitable material of low thermal conductivity, such as fused or molded alumina or silica, natural or 75

artificial mullite, etc., (i. e. material which will transmit only a minor amount of radiant heat from the distributing compartments to the tubes in the heating zone) in order that the tubes may 5 be heated primarily by convection or fluid heat from the hot combustion gases which come into direct contact therewith.

The spent combustion gases having passed over the tubes of the fluid conduit pass from the heating compartments 25, 26 and 27 through openings 37 in the floor 4 of the furnace into the respective gas passageways 38, 39 and 40 from which they pass through a flue 41 to a stack, not shown in the drawings.

15 In the case here illustrated, the size and/or spacing of openings 34, in walls 28, 29, 30, 31, 32 and 33 are so graduated from top to bottom that progressively increasing quantities of combustion gases pass through the openings into contact with 20 the tubes in the heating zone as they pass downward through the furnace. This provides a means of heating the tubes in the lower portion of each bank or row at a higher rate than the tubes in the upper portion of the same row. This condition may, of course, be varied so that greater 25 heat intensity is concentrated around the upper portion, central portion or any desired portion of the tube bank or so that every tube in each or any individual row is heated equally by regulation 30 of the size and spacing of openings 34 to suit requirements. However, both perforated walls of each unit section of the furnace, located on opposite sides of any individual row or bank of tubes, preferably have openings of equivalent 35 size and spacing so that opposite sides of the individual tubes of each tube bank are subjected to substantially equal heating.

In accordance with the features of the present invention, the several tube banks may be heated 40 at a substantially uniform rate or different rates of heating may be employed in any or every tube bank, the conditions of heating being independently controlled in each unit section of the furnace. The use of separating walls, such as indicated 45 in the drawings by the numbers 35 and 36, for the purpose of separating adjacent distributing zones 19 and 20 or 21 and 22 is optional but has been found advantageous in case it is desired to employ different heating conditions in adjacent tube banks.

Another specific form of furnace structure somewhat different from that just described but embodying the features of the present invention, is illustrated in Figures 3 and 4 of the attached 55 diagrammatic drawings.

The main furnace structure comprises side walls 51 and 51', end walls 52 and 52', a roof 53 and a floor 54. The fluid conduit or heating coil comprises a plurality of tube banks 55, 56 and 57, each comprising a vertical row of tubes 58 horizontally disposed between the end walls 52 and 52'. The tubes of each of the vertical rows or banks are connected in series by means of suitable headers or return bends 59. Inlet and outlet ports 60 are provided at opposite ends of each bank of tubes, each of which may be utilized as either the inlet or the outlet port so that the flow of oil, or other fluid to be heated, may be either upward or downward through any individual bank of tubes, as desired.

In this particular form of furnace structure the firing and combustion tunnels 61, 62, 63, 64, 65 and 66 are located within the main furnace structure, one firing and combustion zone being provided on each side of the several tube banks

55, 56 and 57. The firing and combustion compartments are supplied with any desired form of fuel by means of suitable burners, not shown in the drawings, through firing ports 74 which are here shown in the roof of the furnace but may, when desired, be located in the end walls of the firing compartment or both the top and end walls. Walls 84, 85, 86, 87, 88 and 89 separate the firing and combustion compartments 61, 62, 63, 64, 65 and 66 from the respective distributing zones 10 68, 69, 70, 71, 72 and 73 and openings 67 beneath each of these walls permit the passage of hot combustion gases from the firing and combustion compartments into the distributing compartments.

15 Perforated walls 78 and 79, located on opposite sides of the vertical row or bank of tubes 55, define heating zone 75 and separate it from the adjacent distributing zones 68 and 69 respectively. Similar perforated walls 80 and 81 located on 20 opposite sides of the vertical row or bank of tubes 56, define heating zone 76 and separate it from the adjacent distributing zones 70 and 71, respectively. In the same manner, perforated walls 82 and 83, which are located on opposite 25 sides of the vertical row or bank of tubes 57, define heating zone 77 and separate it from the adjacent distributing zones 72 and 73, respectively.

A wall 95, the use of which is optional, serves to 30 separate firing and combustion zones 62 and 63 while a similar wall 96 may be provided for the purpose of separating combustion zones 64 and 65.

In this manner the furnace here illustrated is divided into three unit sections, each of which 35 comprises a vertical row or bank of tubes within a heating zone with a distributing zone and a firing and combustion zone located on opposite sides of each bank of tubes, making each section of the furnace structure symmetrical on opposite 40 sides of the vertical center line through the tube bank, as viewed from the end of the tubes as in Figure 3.

Equalized firing conditions are employed in both firing and combustion compartments of each 45 unit section of the furnace and, due to the symmetry of the furnace structure on opposite sides of each tube bank, equal quantities of hot combustion gases are directed to opposite sides of the tubes in each bank through perforations or 50 openings 90 in walls 78, 79, 80, 81, 82 and 83, said combustion gases passing downward over the tube surfaces in such a manner as to heat the opposite sides of each individual tube equally.

Firing conditions may be so controlled that 55 combustion is substantially completed in the firing tunnels 61, 62, 63, 64, 65 and 66 or some combustion may be allowed in the distributing compartments 68, 69, 70, 71, 72 and 73. Particularly in the latter case, however, the walls 78, 79, 80, 60 81, 82 and 83 are constructed of suitable material of low thermal conductivity, such as fused or molded alumina or silica, natural or artificial mullite, etc., (i. e. material which will transmit only a minor amount of radiant heat from the 65 distributing compartments to the tubes in the heating zone) in order that the tubes may be heated primarily by convection or fluid heat from the hot combustion gases which come into direct contact therewith.

70 The spent combustion gases having passed over the tubes of the fluid conduit pass from the heating compartments 75, 76 and 77 through openings 91 in the roof 53 of the furnace into the respective gas passageways 92, 93 and 94 from which 75

they pass through a flue 97 to a stack, not shown in the drawings.

In the case here illustrated, the size and/or spacing of openings 90 in the walls 78, 79, 80, 81, 5 82 and 83 are so graduated from top to bottom that progressively decreasing quantities of combustion gases pass through the openings into contact with the tubes in the heating zone as they pass downward through the furnace. This provides a means of heating the tubes in the lower portion of each row or bank of tubes at a higher rate than those in the upper portion of the same row. This condition may, of course, be varied so that greater heat intensity is concentrated around 10 the upper portion, central portion or any desired portion of the tube bank or so that every tube in the row is heated equally, regardless of its position in the tube bank, by regulation of the size and spacing of openings 90 to suit requirements 15 and/or by regulated firing through burner ports, not shown, located at any desired position in the end walls of the furnace. However, both perforated walls of each unit section of the furnace, preferably have openings of equivalent size and 20 spacing so that the opposite sides of the individual tubes of each tube bank are subjected to substantially equal heating.

Figures 5, 6 and 7 of the attached drawings illustrate diagrammatically the two general types 30 of flow through the heating coil which may be employed in either form of furnace structure above illustrated and described. Figure 5 illustrates parallel flow and Figure 6 illustrates series flow through the heating coil. Figure 7 illustrates 35 a somewhat modified form of series flow arrangement. It will be understood that many modifications of the two general forms may be employed without departing from the scope of the invention.

40 The numerical designations given to the tube banks in Figures 5, 6 and 7 are the same as those in Figures 1 and 2, although the flows illustrated in Figures 5, 6 and 7 apply equally well to the fluid conduit illustrated in Figures 3 and 4.

45 Figure 8 of the attached drawings illustrates five general types of heating curves obtainable with the improved furnace of the present invention. Curve A illustrates a constantly increasing rate of temperature rise through the entire 50 heating coil; curve B illustrates a constantly decreasing rate of temperature rise; curve C illustrates a uniform rate of temperature rise; curve D illustrates a heating curve with a maximum 55 rate of temperature rise in the first stages of the heating coil and curve E illustrates a heating curve with the maximum rate of temperature rise in the latter stages of the coil.

50 Any of the types of heating curves illustrated in Figure 8 may be obtained with either of the furnace structures illustrated and above described and with either parallel or series flow of fluid through the heating coil. For example, when a 60 constantly increasing rate of temperature rise, such as indicated by curve A in Figure 8, is desired with parallel flow through the heating coil, as illustrated in Figure 5, firing conditions are equalized in the several sections of the furnace so that 65 equal heating is obtained in every bank of tubes and the rate of heating is progressively increased from top to bottom of every vertical tube row. When this same type of heating curve is desired with series flow, as illustrated in Figure 6, progressively more severe heating conditions are employed from top to bottom of each tube bank and 70 progressively more severe heating conditions are

employed in the unit sections of the furnace from left to right. With a flow such as illustrated by Figure 7, the same type of heating curve may be obtained by employing progressively more severe 5 firing conditions in the unit sections of the furnace from left to right and by alternating the firing conditions around adjacent tube banks, progressively increasing heat intensities being employed from top to bottom of the first tube bank, progressively increasing heat intensities being 10 employed from bottom to top of the second tube bank and so on through any number of tube banks in the fluid conduit. In a similar manner, by suitable regulation of the firing conditions, curves of the type illustrated by curves B, C, D and E in 15 Figure 8 may be obtained with flows through the fluid conduit such as illustrated in any of the Figures 5, 6 and 7 or in any modification of the flows illustrated.

As a specific example of the increased efficiency 20 obtainable by use of the features of the present invention in either of the furnace structures illustrated and heretofore described, we will consider two cases. In the first case convection heating by conventional methods is employed wherein 25 hot combustion gases are passed downward through a bank of tubes without any provision for directing them equally toward opposite sides of each tube. In this case the combustion gases entering the tube bank may be at a temperature 30 of about 1650° F., for example, and may leave the tube bank at a temperature of approximately 900° F. In the second case, utilizing the principles of the present invention in a furnace structure such as illustrated and above described, the 35 hot combustion gases are directed equally to opposite sides of each tube and every tube of the heating coil is subjected to substantially the same heat intensity by continuously supplying fresh increments of hot combustion gases to the cooled 40 gases passing over the tube surfaces throughout the entire fluid conduit. In this manner the combustion gases surrounding the tubes are maintained at a minimum average temperature of about 1600° F. In each case the oil enters the 45 heating coil at a temperature of about 500° F. and is discharged at a temperature of about 950° F. The log mean temperature difference is approximately 540° F. in the first case and, assuming an average rate of heat absorption of 9 B. t. u. 50 per sq. ft. of tube surface per 1° F. log mean temperature difference, the average rate of heating in the first case is approximately 4900 B. t. u. per sq. ft. per hour. The log mean temperature difference in the second case is approximately 55 890° F. and the rate of heat absorption of tube surface per 1° F. log mean temperature difference may be increased to approximately 11 B. t. u. per sq. ft. of tube surface, or an increase 60 of about 20 percent as compared with the first case, due to more efficient use of the hot combustion gases by directing them equally to opposite sides of the tubes whereby higher average heat intensity is obtained around the entire circumference of each tube. These conditions will give 65 us a heating rate of approximately 9800 B. t. u. per sq. ft. per hour or an increase of about 100 percent over that obtained by conventional heating under the conditions above given.

As a further example of the results obtainable 70 of somewhat different heating conditions which are substantially the same as those given in the second of the above examples except that the temperature of the combustion gases is allowed to decrease from approximately 1650 to about 1400° 75

F. as they pass over the heating coil, these conditions give a log mean temperature difference of about 790° F. and a heating rate of about 8700 B. t. u. per sq. ft. per hour which represents an 5 increase of approximately 78 percent over the rate of heating obtained in the first case.

It will be understood that the conditions given in each of the above examples may be obtained with either series or parallel flow through the 10 heating coil.

It is to be understood that by the term "convection" as used in the above specification and the appended claims I mean heat carried by the gases, which may also be termed "fluid heat".

15 1. I claim as my invention:

1. In a process for heating fluid of the type wherein the fluid is passed through a plurality of banks of conduits of restricted cross section connected in series, each bank disposed within a 20 separate heating zone, the improvement which comprises simultaneously subjecting opposite sides of each fluid conduit to convection heat by contact with directed streams of hot products of combustion, whereby to independently control the 25 heat input over the entire surface of each conduit, and independently controlling the rate of heat input in each bank.

2. In a process for heating fluid of the type wherein the fluid is passed through a plurality of 30 banks of conduits of restricted cross section connected in series, each bank disposed within a separate heating zone, the improvement which comprises uniformly heating opposite sides of each fluid conduit by convection heat from directed streams of hot products of combustion, whereby to independently control the heat input over the entire surface of each conduit and independently controlling the rate of heat input in each bank.

3. In a process for heating fluids of the type wherein fluid is passed through a plurality of banks of conduits of restricted cross section, each bank disposed within a separate heating zone and the several banks connected in series, the 45 improvement which comprises uniformly heating opposite sides of each fluid conduit by convection from directed streams of hot products of combustion whereby to independently control the heat input over the entire surface of each conduit and independently controlling the rate of heat input in each bank.

4. In a process for heating fluids of the type wherein fluid is passed in series through a plurality of banks of conduits of restricted cross section, each bank disposed within a separate heating zone, the improvement which comprises simultaneously subjecting opposite sides of each fluid conduit to heat by contact with directed streams of hot products of combustion, whereby to independently control the heat input over the entire surface of each conduit, and independently controlling the rate of heat input in each bank.

5. In a process for heating fluids of the type wherein fluid is passed through a plurality of banks of conduits of restricted cross section, each bank disposed within a separate heating zone and the several banks connected in series, the improvement which comprises simultaneously subjecting opposite sides of each fluid conduit to convection heat by contact with directed streams of hot products of combustion, whereby to independently control the heat input over the entire surface of each conduit, and independently controlling the rate of heat input in each bank.

75 6. In a process for heating fluids of the type

wherein fluid is passed in series through a plurality of banks of conduits of restricted cross section, each bank disposed within a separate heating zone, the improvement which comprises uniformly heating opposite sides of each fluid conduit by heat from directed streams of hot products of combustion, whereby to independently control the heat input over the entire surface of each conduit, and independently controlling the rate of heat input in each bank.

10 7. In a process for heating fluids of the type wherein fluid is passed in series through a plurality of banks of conduits of restricted cross section, each bank disposed within a separate heating zone, the improvement which comprises simultaneously directing separate streams of hot products of combustion over opposite sides of the fluid conduits in each bank and adding fresh increments of hot products of combustion to each separate stream at various points in its path of 20 flow over the bank, whereby to independently control the heat input over the entire surface of different conduits in the same bank while independently controlling the rate of heat input in each bank.

15 8. In a process for heating fluids of the type wherein fluid is passed in series through a plurality of banks of conduits of restricted cross section, each bank disposed within a separate heating zone, the improvement which comprises simultaneously directing separate streams of hot products of combustion, of equal heating value, over opposite sides of the fluid conduits in each bank and adding fresh increments of hot products of combustion to each separate stream, equally on 30 opposite sides of each bank, at various points in its path of flow over the bank, whereby to equally heat opposite sides of each conduit and independently control the heat input over the entire surface of different conduits in the same bank 35 while independently controlling the rate of heat input in each bank.

40 9. A furnace for heating fluids which comprises, in combination, a plurality of convection heating zones, a plurality of tube banks connected in series and each comprising a plurality of connected tubular elements disposed within a common plane, centrally located in each heating zone, a combustion zone located on opposite sides of each heating zone, perforated walls separating 45 each heating zone from the adjacent combustion zones, said perforated walls serving to shield the tubular elements from radiation from the combustion zones, and means for directing streams of hot combustion gases from the combustion 50 zones to opposite sides of each tubular element of the tube banks.

55 10. In a method for heating fluids wherein a restricted stream of the fluid is passed in series through a plurality of tube banks, each comprising a plurality of series connected, substantially horizontal tubular elements disposed in common vertical plane, the improvement which comprises uniformly heating the opposite sides of each tubular element from directed streams of hot combustion products of approximately equal heat intensity, and independently controlling the heating conditions in each tube bank.

60 11. In a method for heating fluids wherein the fluid is passed in a restricted stream in series through a plurality of tube banks, each comprising a plurality of serially connected, substantially horizontal tubes disposed in a common vertical plane in a separate heating zone, the improvement which comprises directing streams of 65
